**HIGH CAPACITY LIQUID CONTACT
ELECTRICAL SWITCH**
Don T. Eu Daly, Harlingen, Tex.
Filed Aug. 2, 1962, Ser. No. 214,295
5 Claims. (Cl. 200—112)

The present invention relates to a switch for a high voltage and high amperage current.

An object of the present invention is to provide a switch of high capacity which has no moving parts which carry current, one which is sealed against dirt and fumes, one which requires little or no maintenance, and one which is economically feasible.

Another object of the present invention is to provide a high capacity electrical switch which may be shipped dry or shipped filled with the operating liquid, mercury, and one which may be handled and placed in position so as to activate it and to remain activated as long as it is in the upright position.

A further object of the present invention is to provide a high capacity electrical switch which may be used as a current limiting switch, one which may be used as a current limiting switch with either A.C. current or D.C. current, and one which has indicating means for showing when the switch has been overloaded and thrown to the out position.

These and other objects and advantages of the present invention will be apparent to a person skilled in the art from the following description when taken in connection with the annexed drawings, in which:

FIGURE 1 is an elevational view partially in section showing the switch of the present invention in operating condition.

FIGURE 2 is a view similar to FIGURE 1 showing the switch in open or inoperative position.

FIGURE 3 is a view taken on the line 3—3 of FIGURE 1.

FIGURE 4 is a view taken on the line 4—4 of FIGURE 3.

FIGURE 5 is a view taken on the line 5—5 of FIGURE 3.

FIGURE 6 is a fragmentary elevational view partially in section showing how the switch is reset for operation.

FIGURE 7 is a fragmentary view similar to FIGURE 3 showing another embodiment of the present invention, and

FIGURE 8 is a view on an enlarged scale, taken on line 8—8 of FIGURE 7.

Referring in detail to the drawings in which like numerals indicate like parts throughout the several views, the present invention consists in an upright casing 10 having side walls 12 and 14, end walls 16 and 18, and a bottom 20.

Adjacent the end wall 18 within the casing 10 is a well 22 having its upper open end spaced from the upper ends of the side walls and end walls of the casing 10. Projecting upwardly through the bottom 24 of the well 22 is a post 26 through which extends a contact element 28 having the upper end portion free of the post 26.

A charge of mercury, as at 30, is contained within the well 22.

An inverted cup 32, fabricated of a non-conductive material, is normally positioned so that the rim 34 thereof is spaced above the contact portion 28. The cup 32 is connected to the casing 10 for movement from the normal position, shown in FIGURE 1, to a position shown in FIGURE 2 in which the rim 34 is below and spaced from the contact element portion 28.

Inwardly of and spaced from the other end wall 16 and adjacent the upper end of the side walls 12 and 14 is an actuating rod 36 having end portions exteriorly of the side

2

walls 12 and 14, as at 38 and 40, respectively. The rod end portion 40 has an actuating handle 42 connected thereto.

A pair of arms 44 and 46 project outwardly from the rod 36 and are formed integrally with sleeves 45 and 47, respectively, which are circumposed about the rod 36 within the casing 10. Pins 48 carried by the free ends of the arms 44 and 46 support the cup 32 for its upward and downward movement responsive to swinging movement upwardly and downwardly of the arms 44 and 46.

A pin 50 extends between the arms 46 and 44 and is supported thereby and between the arms 44 and 46 is a roller 52 mounted on the pin 50.

Circumposed about the portion of the rod 36 between the arms 44 and 46 is a sleeve 53 formed integrally with an arm 54 of L-shaped configuration. The short leg 56 of the arm 54 forms a stop for one leg of an L-shaped lever 58 pivotally connected to the long leg 60 of the arm 54 by means of a pivot pin 62, as shown most clearly in FIGURES 1 and 2.

The other leg of the lever 58 is pivotally connected by a link 64 to the upper end of a vertically disposed solenoid core 66, the solenoid 68 being mounted within the casing 10 on the bottom 20 thereof.

A spring 70 within the solenoid 68 biases the core 66 to the up position shown in FIGURE 1.

An electrical connector 72 having a portion 74 exteriorly of the wall 16 is embedded in the bottom 20 of the casing 10 and is formed into a helix, at 76, within the solenoid 68. The connector 72 extends from the helix 76 to the contact element portion 28. A ring 78 surrounds the lower end of the post 26 and rests upon the bottom of the well 22. The ring 78 is a connector having a portion 80 exteriorly of the casing 10 adapted for connection to an electrical conduit, as at 82 in FIGURE 2.

A cover 84 extends over the upper ends of the side walls 12 and 14 and the end walls 16 and 18 and is secured thereto by machine screws 86. Projecting upwardly from the cover is a sleeve 88 forming a support for an indicator rod 90 having an indicator or flag 92 on the upper end thereof and having the lower end extending into the casing 10 and threaded engaged in the bottom of the inverted cup 32. A spring 94 within the sleeve 88 biases the rod 90 downwardly, there being provided a collar 96 on the rod 90 against which one end of the spring 94 bears, the other end of the spring bearing against a screw cap 98 which closes the upper end of the cylinder or sleeve 88.

In addition to the charge of mercury 30 contained within the casing 10, there is a charge of a lighter liquid having spark quenching characteristics, as at 100 in FIGURES 1 and 2 and 4 to 6. The liquid of the charge 100 may be transformer oil, sulphur hexafluoride, or the like. A conductive ring 102 surrounds the contact element portion 28 and is secured to the upper end of the post 26.

In operation when the casing 10 is to be installed it is tilted so that all the mercury flows down to the end of the casing having the well 22 and then it is tilted back so that the mercury stays within the well 22 while the other liquid fills the rest of the casing 10 and the space above the cup 32. The cup 32 will also have some of the liquid therein. Upon the forward access current through the solenoid 68 as received from the conductor or connector 72 and traveling through the helix 76, the solenoid core 66 will be drawn downwardly so as to rotate the lever 58 in the counter-clockwise direction from the position shown in FIGURE 1 to the position shown in FIGURE 2. This results in release of the roller 52 from its support on the short leg of the lever 58 and subsequent dropping of the arms 44 and 46 under the action of the spring 94.

This results in forcing of the cup 32 downwardly over the exposed contact portion 28 so as to drive the mercury

out of the cup 32 and upwardly along the sides of the cup 32 in the well 22. As the mercury leaves the contact of the ring 102 any spark between the mercury and the ring 102 will be quenched by the transformer oil of the charge 100.

The switch of the present invention will be then in an out condition and the indicator flag 92 will be the lower position so that an operative after correcting the condition which led to the overcharge of the switch may by rotating the handle 42 downwardly so as to rotate the arm 54 in a clockwise direction from the position shown in FIGURES 1 and 2 to the position shown in FIGURE 6. This results in re-cocking of the lever 58 so that when the handle 42 is returned to the up position the short leg of the lever 58 will again engage the roller 52 and lift the arms 44 and 46 to the up position drawing the cup 32 upwardly and again letting the mercury charge 30 re-establish electrical contact between the contact portion 28 and the ring 78.

In FIGURES 7 and 8, the solenoid is not employed and the arms 44' and 46' are connected directly through the rod 36' to the handle 42'. A detent assembly 104 serves to retain the switch in either the operative condition or the inoperative condition, there being provided two indent recesses in the casing wall, as at 106 and 108 in FIGURE 8.

The use of the second form of the invention is obvious to a person skilled in the art, as being possible to stop the flow of current through the switch by manipulating the handle 42' downwardly and to re-establish current flowing through the switch by lifting the handle 42'.

While only preferred embodiments of the present invention are shown and described other embodiments are contemplated and numerous changes and modifications may be made therein without departing from the spirit of the invention as set forth and established by the appended claims.

What is claimed is:

1. An electrical switch comprising an upright casing including a bottom, opposed side walls rising from said bottom, an end wall connecting each of the adjacent ends of said side walls together and a top extending over the upper ends of said side walls and end walls, a well in said casing, said well having the open upper end thereof spaced below said casing top, a contact element in said well and having a portion spaced above the bottom of said well, an inverted cup mounted within said casing for upward and downward movement between a position in which the rim thereof is above and spaced from said contact element portion and a position in which said cup encompasses said element with the rim below and spaced from said element portion, a charge of electrically conductive liquid in said well and contacting said element when said cup is in the above position, said cup when in the down position being operable to force said liquid out of contact with said element, electrical connection means extending through said casing into contact with said liquid and into connection with said element, and releasable latch means operatively connected to said cup for holding said cup in the above position.

2. An electrical switch comprising an upright casing including a bottom, opposed side walls rising from said bottom, an end wall connecting each of the adjacent ends of said side walls together and a top extending over the upper ends of said side walls and end walls, a well in said casing, said well having the open upper end thereof spaced below said casing top, a contact element in said well and having a portion spaced above the bottom of said well, an inverted cup mounted within said casing for upward and downward movement between a position in which the rim thereof is above and spaced from said contact element portion and a position in which said cup encompasses said element with the rim below and spaced from said element portion, a charge of electrically conductive liquid in said well and contacting said element when said cup is in the above position, said cup when in the down position being operable to force said liquid out of contact with said element, electrical connection means extending through said casing into contact with said liquid and into connection with said element, spring means operatively connected to said cup urging said cup to the down position, and releasable latch means operable to released position upon a flow of current above a predetermined value through the connection means connected to said element operatively connected to said cup for holding said cup in the above position.

3. An electrical switch comprising an upright casing including a bottom, opposed side walls rising from said bottom, an end wall connecting each of the adjacent ends of said side walls together and a top extending over the upper ends of said side walls and end walls, a well in said casing, said well having the open upper end thereof spaced below said casing top, a contact element in said well and having a portion spaced above the bottom of said well, an inverted cup mounted within said casing for upward and downward movement between a position in which the rim thereof is above and spaced from said contact element portion and a position in which said cup encompasses said element with the rim below and spaced from said element portion, a charge of electrically conductive liquid in said well and contacting said element when said cup is in the above position, said cup when in the down position being operable to force said liquid out of contact with said element, electrical connection means extending through said casing into contact with said liquid and into connection with said element, spring means operatively connected to said cup urging said cup to the down position, and releasable latch means including a solenoid operable to released position upon a flow of current above a predetermined value through the connection means connected to said element operatively connected to said cup for holding said cup in the above position.

4. The apparatus according to claim 1 in which said liquid charge is mercury.

5. The apparatus according to claim 4 together with a charge of other liquid floating on said mercury, said other liquid having a spark-quenching characteristic.
